Patented June 27, 1922.

UNITED STATES PATENT OFFICE.

JOHN A. BISHOP, OF CLEARWATER, FLORIDA.

OIL-BURNING APPARATUS.

1,420,957.

Specification of Letters Patent. Patented June 27, 1922.

Application filed September 9, 1920. Serial No. 409,220.

To all whom it may concern:

Be it known that I, JOHN A. BISHOP, a citizen of the United States, residing at Clearwater, in the county of Pinellas and State of Florida, have invented certain new and useful Improvements in Oil-Burning Apparatus; and I do hereby declare the following to be a full, clear, and exact description of the invention, such as will enable others skilled in the art to which it appertains to make and use the same.

This invention relates to the art of burning liquid fuel, more particularly heavy oils.

Its object is to secure complete combustion of a fuel oil.

It consists of a system adapted in its entirety to preliminarily heat heavy oil and then by further treatment transform it into a gas or vapor, free from liquid spray or drops, and to burn said gas as soon as it has been generated. It also consists of various subcombinations as will be more fully set forth in the ensuing description and defined in the appended claims.

25 In the drawing: Figure 1 is a diagrammatic illustration of a plant or system embodying my invention; Figure 2 is a diagram showing the disposition of the burner on the end of the fuel pipe disposed within a fire chamber.

According to this invention it is contemplated that fuel oil shall be drawn from a suitable storage reservoir of large capacity, into a preliminary heater adapted to contain a relatively small volume of oil in order that the same may be quickly heated; that the preliminarily heated oil shall be pumped or otherwise fed from said preliminary heater through a straining and settling tank where-in the sediment, or heaviest constituents of the fuel oil, may separate from the more fluid portions and the latter flow upward through a strainer or filler into a retort heated to a relatively high temperature, say 350° to 400° F., by steam or other hot aeriform fluid, gas generated in the retort flowing thence to a burner disposed within the fire chamber of a boiler, or wherever it may be desired to burn said gas.

50 In the drawings, 1 indicates a preliminary heater preferably divided into two parts by a central partition 2, each part containing a steam heating coil. A pipe 3 is shown adapted to conduct oil from a storage reservoir

(not illustrated) into said heater, and said pipe 3 may, preferably, communicate with two branches 4 and 5, each controlled by a valve 6 or 7, said branches leading, respectively, into the heater compartments 1^a and 1^b. From the bottom of each heating compartment 1^a and 1^b extend sediment pipes 8 and 9 each controlled by a valve 8^a, 9^a, and connecting with a drain pipe 10. The particular form and arrangement of the preliminary oil heater, however, is not material to my invention, the essential factor with respect thereto being that said heater shall be constructed so as to heat relatively small volumes of oil for purposes of conserving heat; the particular means, therefore, for heating the oil in relatively small volumes may be varied widely without departing from the spirit of my invention. An auxiliary boiler is illustrated at 11, as an example of a means whereby heat may be developed for heating the oil in said preliminary heater, steam coils 12 and 12^a being shown whereby heat may be exchanged between steam drawn from the boiler 11 and the oil in said heater.

80 Numeral 20 indicates a separating tank, preferably insulated by a covering 20^a, adapted to receive heated oil from the preliminary heaters through a pipe 21, controlled by valves 21^a and 21^b, said pipe being connected with two branches connected at 22 and 23 with the respective heating chambers 1^a and 1^b and controlled by suitable valves (not shown). Pipe 21 enters the lower portion of separator 20 and discharges oil downward thereinto through openings 24. A pump, shown diagrammatically at 25, feeds oil through said pipe 21 from one or both of the heaters to the separator 20. Above the end of pipe 21 in separator 20 is a filter or strainer 26, through which the lighter, more volatile heated oil passes upward, while the sediment and viscous heavy matter tends to settle in the bottom of the separator, whence it may be drained away through pipe 27 controlled by valve 27^a, and be conducted to any suitable receptacle or place of use.

85 The oil filtered through the strainer 26 passes upward through the pipe 30, controlled by valve 30^a, to the pipe 31 which delivers to the interior of a retort or fluid tight chamber 40, which is disposed within a

fluid tight casing or drum 50. Said retort 40 has within it a heating drum 41, the ends of which are connected by pipes 42 and 43 with the space between the outer wall of 5 said retort 40 and said casing or drum 50. The said retort 40 is filled with wires, small rods, tubes or fragments of metal 44, or may be constructed with its interior space occupied by any suitable bodies, whereby the 10 oil fed to the interior of said retort is so broken up as to present an exceedingly large evaporating surface. Communicating with the interior of the casing or drum 50 is a steam pipe 51 having a valve 51^a, and connected to a main 52 controlled by a valve 52^a. Said main 52 is also connected by a branch 15 54, having a valve 54^a, to the branch pipe 31, which conducts oil into the interior of said retort or drum 40. The steam pipe or 20 main 52 is shown as deriving its steam from the steam space of a boiler 60, indicated conventionally.

Communicating with the lower end of retort or fluid tight chamber 40 directly 25 opposite the oil pipe 31, is a gas pipe 61 leading to a burner or gas outlet nozzle 62, said burner or nozzle 62 being of any suitable type but preferably having a gas outlet or outlets restricted in size with respect to 30 the size of the gas pipe delivering the gas to said burner. A suitable pipe 63 controlled by a valve 63^a is arranged to carry off condensed water and sediment from the heating drum 50 to a boiler, feed water heater (not 35 shown), or elsewhere. The drum 50 is preferably incased with a heat insulating coating composition 64 of any approved construction, such as an asbestos or magnesia mixture.

40 If desired, the small auxiliary boiler 11 or other auxiliary steam generator may be utilized not only for the purpose of supplying steam for the coils of the preliminary heaters 1^a and 1^b but also for the purpose 45 of providing steam to start the burner 62, as will be presently explained, the steam space of said boiler 11 being connected by pipe 65 with the steam main 52, a valve 65^a controlling the passage of steam.

50 Connected with the pipe 21, which conducts oil from the preliminary heater to the separator 20, is a by-pass pipe 70, from which two branch pipes 71 and 72 controlled by valves 71^a and 72^a, lead to the chambers 55 1^a and 1^b. All oil fed by the pump 25 that is in excess of the oil required by the retort 40 in the process of generating gas is returned by the pipe 70 and branches 71 and 72 to the preliminary heater, the quantity of oil fed 60 to the retort being thereby automatically regulated.

The invention is based upon the assumption that liquids cannot be burned while in a liquid state but must first be converted into 65 a gaseous state, either at the instant of

combustion, or some time previously thereto, and that completeness of combustion can most surely be achieved by converting the liquid into gas an appropriate time before attempting to burn it. Liquids, as is well 70 known, may be atomized or broken into a very fine spray, mixed with air or oxygen, and fired, the firing gasifying at least partially the fine liquid particles so that flame 75 is produced. In my invention it is the intention to gasify a liquid hydrocarbon in a retort or other closed chamber and conduct the gas produced to a burner so that said hydrocarbon issues from the burner in the form of gas which may be ignited and 80 completely consumed so as to extract from it all possible heat.

In operating the apparatus described the oil will first be heated in one of the preliminary heaters and pumped through the 85 separator 20 into the retort 40, at first only a small quantity of oil being admitted through pipe 31. Steam generated in the auxiliary boiler 11 is conducted through pipes 65 and 54 into the pipe 31 under high 90 pressure, the said steam breaking up the oil in the retort among the filling material into fine particles, imparting high heat to it and forcing it along through the pipe 61 and out through the burner 62 in a partly gaseous and partly finely divided liquid state. Coming from the burner in an atomized and 95 partially gasified condition it may be ignited in the fire chamber beneath the boiler. This process may be kept up and the fuel burned 100 as an atomized and partially gasified oil until the heat generated in the fire chamber has developed a high steam pressure in the boiler 60. When the pressure in the boiler 105 is high enough to attain a temperature of 350° to 400° F. steam will be admitted through the main 52 and pipe 51 into the heating drum 50, whence it will fill the inner drum 41 within the retort 40 as well as the outer drum 50 surrounding it. With a 110 gage pressure of 150 pounds, a temperature of 365° F. may be obtained within the drum 51, which is generally sufficient to vaporize the preheated fuel oil within the retort 40, which presents a very large evaporation surface by reason of the presence of the filling material. Steam may now be cut off from the branch pipe 54, and pure oil gas then 115 issues through the pipe 61 and from the burner 62, the combustion of which is complete. 120

Should carbon form within the retort 40, or other sediment or viscous matter clog the retort, steam may be blown therethrough from the branch pipes 54 and 31 for the 125 purpose of cleaning out said retort and the gas pipe 61. The entrance of the steam to retort 40 being opposite the gas outlet 61, it will be clear that the cleansing effect of the steam will be thorough.

It will be understood that all steam pipes and other pipes for conducting heated fluids may be covered with heat insulating material, and that all containers of heated fluids 5 may be similarly insulated, as indicated in the drawings with respect to the casing or drum 50 and separator tank 20. It will also be understood that the retort 40 and casing 50 must be made of sufficient strength to 10 withstand the high pressures to which they are subjected.

It is contemplated that filler material such as wires, small tubes, or other objects 61^a adapted to subdivide a body of fluid flowing 15 through the gas pipe 61 shall be inserted or formed in a part of the pipe 61 that is within the combustion chamber where the fuel is to be burned and shall be so disposed as to be highly heated by the burning gases 20 or vapors issuing from the burner 62. The presence of the bodies 61^a causes the gases, vapors and liquids that may pass through said pipe under the pressure of steam admitted to the retort 40 in starting, to be so 25 divided as to present a large surface to the heat of combustion in the combustion chamber and speedily effect complete gasification of all the oil passing therethrough, so that it issues from the burner in gaseous form. 30 Furthermore, in using the system with low pressure boilers that may not afford sufficient steam pressure in the casing 50 to completely convert the oil in the retort 40 into gas, such unconverted liquid oil as may enter the gas pipe 61 will be converted to gas 35 within that portion of the pipe 61 that is within the combustion chamber and contains the wires or filler material 61^a.

Figure 2 is a diagram of the disposition 40 of a burner 62 and of the gas pipe 61 and filler 61^a in the combustion chamber of a horizontal boiler. The pipe 61, in this embodiment, enters the front of the combustion chamber, extends to the rear, and has 45 its burner nozzle recurved so as to direct a stream of gas or vapor, and atomized liquid oil, if liquid oil be present, toward the front in a direction opposite that in which the incoming air for supporting combustion moves. After ignition the hot burning gases eddying and swirling owing to the stream of ignited gases and vapors mingling with the air currents, heat the pipe 61 in closing 50 the bodies 61^a to such a high temperature 55 that all oil will be converted into gas or vapor before it issues from the burner orifice.

Having described my invention so as to enable those skilled in the art to make and 60 use the same, what I claim and desire to secure by Letters Patent is:

1. In apparatus of the class described, an air tight casing, a retort within said casing spaced from the wall thereof, a heating 65 drum within said retort, said heating drum

being in communication with the space within said casing around said retort, a pipe communicating with said retort adapted to admit oil thereinto, a gas pipe leading therefrom, and means adapted to admit heated 70 aeriform fluid under pressure into said casing.

2. In apparatus of the class described, a fluid tight casing adapted to confine hot fluid under pressure, a retort within said 75 casing, filler devices within the retort for producing a large heating surface therein, a pipe for admitting fuel oil into said retort through said casing at its upper end, a gas pipe leading from the lower end of said 80 retort, and means for admitting heated aeriform fluid under pressure into the casing surrounding the retort.

3. In apparatus of the class described, a retort, filler devices for producing a large 85 heating surface within said retort, a conduit for admitting fuel oil into said retort at one end, a conduit for admitting heated aeriform fluid into said retort at the same end, and a gas conduit leading from the retort at 90 a point opposite the inlet for the aeriform fluid.

4. In apparatus of the class described, a retort and means for heating it, a pipe for admitting fuel oil into said retort at one end, 95 a gas pipe leading from the opposite end of said retort, filler devices within said retort for producing a large heating surface therein, and a pipe connected to the oil inlet pipe adapted to admit heated aeriform fluid under pressure. 100

5. In apparatus of the class described, a fluid tight casing adapted to confine hot fluid under pressure, a retort within said casing spaced from the wall thereof, means 105 for admitting heated aeriform fluid under pressure into said casing, a pipe for admitting fuel oil into said retort at one end, a gas conduit leading from the opposite end of said retort to the exterior of said casing, 110 filler devices within the retort for producing a large heating surface therein, and a pipe connected to the oil inlet pipe adapted to admit heated aeriform fluid under pressure into said retort through said oil inlet. 115

6. In apparatus of the class described, a retort, a fluid tight casing surrounding said retort and adapted to confine hot fluid under pressure, means for admitting a heated aeriform fluid into said casing, an oil heater, 120 means for conducting oil from said heater to said retort, a burner located outside of the casing and a gas pipe leading from said retort to said burner.

7. In apparatus of the class described, a 125 retort, a fluid tight casing surrounding said retort and adapted to confine hot fluid under pressure, means for admitting a heated aeriform fluid to said casing, an oil heater, a separator, means for conducting oil from 130

- said heater through said separator to said retort, a burner located outside of the casing and a gas pipe leading from said retort to said burner.
5. In apparatus of the class described, a retort and means for heating it, an oil heater, a valved conduit connecting said oil heater and said retort, a pump for forcing oil through said conduit to said retort, a 10 by-pass pipe connecting said heater with said conduit on the delivery side of the pump, a burner, and a gas outlet pipe leading from the retort to said burner.
9. In apparatus of the class described, a 15 retort, a fluid tight casing surrounding said retort, an oil heater, a valved conduit connecting said oil heater with said retort, means for admitting aeriform fluid under pressure into said casing, a burner, a gas 20 pipe leading from said retort to said burner, a pump for forcing oil through said valved conduit, and a by-pass pipe leading from said conduit on the delivery side of said pump to said oil heater.
25. 10. The combination of an oil heater, a steam generator for supplying heat to said oil heater, a fluid tight casing, a retort within said casing spaced from the wall thereof, means for conducting oil from said 30 heater to said retort, a steam pipe leading from the steam space of said steam generator into the oil pipe leading into the retort, a conduit for conducting steam to the interior of the casing, a burner and a gas pipe 35 leading from the retort to the burner.
11. The combination of a main steam generator, an auxiliary steam generator, a retort, a fluid tight casing surrounding said retort and spaced therefrom, means for supplying 40 steam from the main generator to said casing, means for supplying steam from the auxiliary generator to said retort, means for admitting oil into said retort, and a gas pipe leading from said retort to the combustion chamber of said main generator.
45. 12. The combination of a main and an auxiliary boiler, an oil heater and means for supplying heat thereto from the auxiliary boiler, a fluid tight casing, a retort within said casing, a conduit for conducting oil from the oil heater into said retort, a gas outlet pipe leading from said retort to the combustion chamber of said main boiler, a steam main connected with the steam space of both boilers, branch pipes leading 50 from said main into said casing and said retort, respectively, and suitable valves for controlling the passage of steam from either boiler to the said casing and retort.
55. 13. In apparatus of the class described, a 60 retort, a fluid tight casing surrounding said retort, a conduit for admitting fuel oil into said retort, means for admitting aeriform fluid under pressure into said casing, a combustion chamber, and a gas pipe leading 65 from said retort into said combustion chamber, said gas pipe inclosing filler material within that part thereof which is within the combustion chamber.
14. In apparatus of the class described, a 70 retort, a conduit for admitting fuel oil into said retort, a conduit for admitting steam into said retort, a gas outlet pipe connected with said retort at a point opposite the inlet of said steam conduit, a combustion 75 chamber, said gas outlet pipe extending into said combustion chamber and discharging thereinto, and said gas pipe inclosing filling material in that part which is within the combustion chamber.
80. In testimony whereof I affix my signature.
JOHN A. BISHOP.
